HAT BRIM IRONING MACHINE

**Paul Schultze, Danbury, Conn., assignor, by
mesne assignments, to Doran Brothers, Incorporated,
Danbury, Conn., a corporation of Connecticut**

Application June 16, 1933, Serial No. 676,081

29 Claims. (Cl. 223—21)

My invention refers to ironing machines and especially to a machine for ironing the brims of hats.

The object of the invention is to provide a brim ironing machine of simple and practical construction which will be durable and dependable in action. Further to provide a machine for the above purpose including two heated ironing elements, one for operating upon the underside of the brim and the other for operating upon the top side of the brim, the element for the underside of the brim being in the form of a rotatable cone-shaped iron, while the element for the top side of the brim neither rotates nor reciprocates, but simply smoothes the top surface of the hat brim while the brim passes beneath in an oval manner and on a true vertical axis.

Another object is to provide a brim iron wherein the hat, together with the block upon which it is mounted, is raised and lowered bodily so as to feed irregular shaped brim portions between the operating irons.

Another object is to design a hat brim ironing machine of the class specified wherein the lathe upon which the hat block and hat are mounted is, at all times, operated in a true vertical position and adapted to be not only raised and lowered to accommodate the brim to the ironing elements, but to provide means for causing the lathe to travel toward and away from said ironing elements in an irregular oval path better to compensate for the oval shape of the hat and its brim.

The invention, therefore, resides in the particular construction and combination of elements and cooperation of parts as will be hereinafter more fully explained and particularly set out in the claims to follow.

In the drawings

Fig. 1 shows a left side elevation of my improved brim ironing machine complete with hat mounted on the spindle of the machine as in course of operation;

Fig. 2 is a front view of the machine shown in Fig. 1, pedestal broken away and hat indicated on spindle in dotted lines;

Fig. 3 shows a top plan view, the parts being in the position shown in Fig. 1 with hat removed;

Fig. 4 is a front view, on reduced scale, of a hat and irons positioned in relation thereto, as while operating on the side brim of a hat;

Fig. 5 shows a central vertical section through the machine taken on line 5—5 of Fig. 2; and

Fig. 6 is a sectional plan view showing the lathe cam in section and geared to rotate the oval lathe.

Referring to the characters of reference marked upon the drawings, 10 represents a pedestal which may be formed of cast metal and in the upper part having openings 11 and 12, see Fig. 5, through its front and rear wall, better to permit of assembling. The top face of the pedestal is finished off to form a flat top surface upon which brackets 13 and 14 are mounted. The bracket 13 is shaped and machined to accommodate the several parts, of the machine, which are carried thereby, including two table or plate-like members 15—15, see Figs. 2, 3 and 5, which are adapted to support and guide the brim of the rotating hat to insure that said brim properly enters and passes between the heated irons. The top surface of 15 these table members are on a plane with that of the underside of the brim of the hat so that in the rotation of the latter, it will move over the surface of the table while being ironed, due to the rotation of the lathe and the movement of the 20 ironing elements.

The bracket 14, see Figs. 5 and 6, which is supported on the top surface of the pedestal also has a top finished surface upon which the cam gear 16 moves in its rotation and travels in an irregular oval path. This bracket 14 includes a central opening 17 through which the bearing 18 for the lathe spindle 19 extends and whereby it is permitted to travel in its oval path for the rotation of the hat with respect to the ironing elements. A cam 20 is secured to the spindle bearing 18 by means of nuts 21 mounted upon the lower threaded end portion of the bearing 18. The depending oval annular edge portion 22 of the member 20 is shaped to form the cam proper and serves for the engagement of a roller 23 carried on the forward end of a lever 24 that is pivotally hung to the bracket 14 as shown in Fig. 2. The purpose of this cam and operating lever is to impart vertical movement to the rod 70 which 40 hinged supports the operating arm 25, as will again be referred to.

The machine may be operated from any suitable source such for instance as an electric motor, not shown, but which in practice is usually attached to the pedestal and connected to drive the sprocket 26 mounted on shaft 27 journaled in depending hangers 28 of the beforementioned bracket 13. From this shaft 27, I provide two operative driving connections, one for operating 50 the beforementioned oval lathe spindle 19 and for tilting the top iron and the other connection for rotating the lower ironing element. The latter connection is made from a sprocket 29 through a sprocket chain 30 that serves to drive 55

a pinion 57 mounted upon its upper end and exposed to engage the teeth of the oval cam gear 16 for the purpose of rotating the same in a way to slowly rotate the spindle and cause it to travel in an oval path. This member 16 includes a cam groove 58 formed in the under face of the gear and is also of an oval shape corresponding to that of the oval gear 16, and serves to receive and engage the spaced apart guide rollers 59-59 that are mounted upon studs 60-60 secured to 10 the bracket 14 in juxtaposition to the axis of the gear 57.

The rollers 59 serve to guide the axis of the oval gear and lathe spindle in a path, as suggested by dot and dash line x , see Fig. 6, which insures that 15

Whichever party may be in power, it is the duty of the Government to maintain law and order, and to protect the lives and property of all its subjects, and to do this it is necessary that

for the operator to place his foot on the pedal 49 in order to release the chuck 46 and permit the hat block with hat fitted thereon to be placed thereon, the chuck of the spindle entering central hole 75 in the block and the pin 76 of the spindle engaging a hole in the block. The pedal would next be released, to allow the chuck to expand and clamp the block to the spindle. The machine may thus be started, causing the cone roller iron 10 and the lathe to both slowly rotate.

The operating lever 25 would next be moved in from the rest 14 to position the top iron 62 upon the top brim of the hat in close proximity to the band portion. With the parts in this position, the 15 lathe slowly rotates, causing the brim of the hat to pass over the lower cone roller iron and beneath the heated top iron, the eccentric movement provided for the lathe causing it to travel during its rotation in a true vertical position in 20 an oval path, better to accommodate the oval shape of a hat and to keep its band portion in close proximity to the inner face or side of the top iron. The lathe spindle is also given a longitudinal movement during its rotation in order that 25 the hat will be slightly raised and lowered, better to accommodate a scoped hat and to feed both the ends and side portions of the brim between the irons and at a right angle to the axis of the lathe. The rotation of the lathe and operation 30 of the machine obviously continues in this manner until the brim has been completely ironed, after which it is removed from the lathe and replaced by another hat.

The foregoing described illustration of my improved hat brim ironing machine represents one embodiment of its construction, yet it will be understood that various changes may be made therein without departure from the spirit of the invention or the scope of the claims.

Having thus described my invention, what I claim and desire to secure by Letters Patent is:

1. A hat brim ironing machine comprising a rotatable iron and a companion iron and means for heating the same, a supporting arm, the said 45 companion iron being flexibly supported on the arm, means for raising and lowering said arm, and means for tilting the companion iron to conform to the position and shape of the hat brim.

2. A hat brim ironing machine comprising a conical ironing roller, a flat faced iron positioned above the ironing roller, means for heating said irons, a non-tiltable lathe and hat supported thereon, means for rotating the lathe, means for raising and lowering the lathe spindle during its 55 rotation, and means for moving the rotating spindle in an oval path to and from the said irons to feed the hat brim therebetween.

3. A hat brim ironing machine comprising a cone ironing roller, a flat faced iron, means for heating the same, a lathe adapted to support a hat, means for rotating the lathe in a manner to feed the brim of the hat between the ironing roller and iron, a cam carried by the lathe and engaging said ironing roller to impart longitudinal movement to the lathe during its rotation.

4. A hat brim ironing machine comprising an iron for ironing the underside of the hat brim, an iron for ironing the top side of the brim, means for heating the irons, a lathe adapted to support a hat block and hat thereon, means for rotating the lathe for feeding the brim of an oval hat between the irons, an arm for movably supporting the top 70 iron and rod to which the arm is hingedly sup-

ported, and means actuated by the lathe to operate the rod and arm.

5. In a hat brim ironing machine, the combination of an iron adapted to operate in a fixed plane and means for heating the same, of an oval gear having an oval cam groove formed therein, an elongated bearing carried by the gear, a lathe spindle mounted for longitudinal movement in the bearing and adapted to be driven therewith, and means for rotating the oval gear to rotate 10 and move the lathe in an oval path, and means to move the lathe and hat longitudinally.

6. In a hat brim ironing machine, the combination of a frame, a pair of irons and means for heating the same, an oval gear mounted for float- 15 ing movement on the frame, said gear having an oval cam groove formed therein, adapted to guide the movement of the axis of said oval gear, a driving pinion meshing with and driving the oval gear, guide rollers secured to the frame and engaging 20 the cam groove in spaced relation to each other and the driving pinion, an elongated bearing carried by the gear, a lathe spindle mounted for sliding movement in the bearing and adapted to be driven therewith, and a hat block and hat mount- 25 ed thereon.

7. A hat brim ironing machine comprising a top iron, a roller shaft, an ironing roller mounted thereon, a tubular bearing member, a heatable element upon the bearing member and within the 30 ironing roller, a lathe adapted to support a hat block and hat thereon, and means for rotating the lathe to feed the hat brim between the iron and roller.

8. A hat brim ironing machine comprising a 35 driven shaft, a conical ironing roller mounted thereon, a bearing for said shaft, a conical-shaped heatable element supported on the bearing and within the conical-shaped ironing roller, a lathe adapted to support a hat block and hat thereon 40 and means for rotating the lathe, cam means intermediate the roller and lathe for raising and lowering the latter by the former, and means for moving the rotating lathe through an oval path.

9. A hat brim ironing machine comprising a 45 top iron, a shaft, an ironing roller mounted thereon, a tubular bearing member, a heatable element upon the bearing member and within the ironing roller, a lathe adapted to support a hat block and hat thereon, an oval gear and cam for ro- 50 tating the lathe to feed the oval shaped hat brim between the iron and roller, and means for rotating the oval gear and cam.

10. In a hat brim ironing machine, the combination of a lathe adapted to support and rotate 55 a hat, a rotatable cone shaped iron to support and iron the underbrim of a hat carried on the lathe, a vertically movable supporting rod, an operating arm hingedly connected to the rod, an iron hinged to the arm for side-wise swinging move- 60 ment, and means for raising and lowering the rod and its arm to tilt the iron during the movement of the hat brim thereunder.

11. In a hat brim ironing machine, the combination with a lathe having means for rotating 65 the same, a hat block and hat carried by the rotatable lathe, irons adapted to iron the brim of said hat, and means for guiding the axis of the lathe spindle in an oval path to feed the brim with a constant peripheral velocity past and be- 70 tween the heated irons.

12. A hat brim ironing machine comprising means to support and rotate an oval hat about an always vertical axis, irons adapted to iron the brim of said hat, means to move said hat about 75

tical axis of rotation through an oval path to feed the brim through said ironing means.

13. In a hat brim ironing machine, the combination of means to support and rotate a scoped 5 and oval hat about an always vertical axis, irons adapted to iron the brim of said hat, means for bodily moving said support through an oval path to properly feed the brim through said ironing means, and means operative while the hat is rotating to move the hat longitudinally to said vertical axis to compensate for said scope of the crown and brim.

14. In a hat brim ironing machine, the combination of an upper and a rotating lower iron, 15 an always vertical lathe spindle having means for supporting and rotating an oval hat, cam means to guide the axis of the said always vertical lathe spindle in a path to insure that the point of contact between the crown of the hat and 20 front face of the upper iron remains in substantially the same position at all times during the rotation of the hat.

15. In a hat brim ironing machine, the combination of a lathe adapted to support and rotate 25 a hat about a vertical axis, irons adapted to iron the brim of said hat, means to move the lathe through a horizontal oval path while keeping its axis in a vertical position to feed the brim through said ironing means, means for raising and lowering 30 the lathe spindle and its hat during said movement, and means for tilting the upper iron in the direction of the path of movement of the hat brim to conform to the scope of said hat during the movement of said brim past and between the 35 irons.

16. In a hat brim ironing machine, the combination of means to support and rotate a scoped and oval hat, irons one above the other adapted to iron the brim of said hat, the lower iron having 40 a curved face to contact with the underside of the hat brim, means for supporting the top iron to permit it to tilt about an axis substantially parallel to the radius along which said curved face of the lower iron contacts the under side of 45 the brim to conform to the scope of the hat and brim, and means to move the hat support in a non-tilting vertical position through a horizontal oval path to feed the brim through said ironing means.

50 17. A hat brim ironing machine comprising a rotatable iron and means for heating the same, a second but substantially stationary iron operating in conjunction with the rotatable iron, a lathe adapted to support an oval hat block and hat thereon, means adapted to rotate said lathe about an always vertical axis and means for moving the 55 rotating lathe while keeping its axis in a vertical position in a predetermined path to and from the irons.

60 18. A hat brim ironing machine comprising a rotatable iron and means for heating the same, a second substantially stationary iron operating in conjunction with the rotatable iron, a lathe to support an oval hat block and hat thereon, means 65 to rotate said lathe, means for moving the rotating lathe while keeping its axis in a uniformly vertical position to and from the irons, and means to raise and lower the hat while being rotated and moved toward and from the irons.

70 19. A hat brim ironing machine comprising a curved rotatable under iron and means for heating the same, a substantially stationary and flat upper iron operating in conjunction with the rotatable iron, a lathe including a slidably mounted 75 spindle to support an oval hat block and hat

thereon, means to rotate said lathe, means for moving said spindle longitudinally to shift the hat with respect to the irons in accordance with the scope of the hat, and means for moving the rotating lathe while keeping its axis in a uniformly vertical position through a path which compensates for the oval of the hat. 5

20. A hat brim ironing machine comprising a curved and rotatable iron, a second substantially stationary iron operating in conjunction with the 10 rotatable iron, means for heating said irons, a lathe having a spindle to support an oval hat block and hat thereon, means adapted to rotate said lathe, cam means for guiding the rotating lathe so that the axis of its spindle and hat thereon 15 move while in a vertical position through a predetermined substantially oval path during each complete revolution, and cam means to raise and lower the lathe spindle in timed relation to the movement of said spindle axis through said oval 20 path and while being rotated.

21. A hat brim ironing machine comprising a base, a rotatable support, a lathe spindle carried by said support, means for ironing the brim of an oval hat carried by said lathe spindle while 25 the latter is rotated, said lathe and rotatable support being movably mounted on said base, and operating means between said rotatable support and said base to shift the support with respect to the base to compensate for the oval of the hat and 30 thereby keeping the brim in proper operative relation to said ironing means.

22. A hat brim ironing machine comprising a conical rotatable iron, a flat-faced iron, means for heating the same, a lathe adapted to support 35 an oval hat block and hat thereon, means for rotating the lathe on a vertical axis, and means for bodily shifting the rotating lathe in a horizontal direction so that the axis of the lathe moves in a predetermined oval path to feed the 40 brim of an oval hat past and between the irons and maintains said brim at substantially the same distance from the inner edge of the conical iron at all times during rotation of the hat.

23. A hat brim ironing machine comprising a 45 pair of irons and means for heating the same, a lathe and an oval hat supported thereon, means for rotating the lathe, means for bodily shifting the rotating lathe so its axis moves in a substantially oval path and at all times in uniform angular 50 relation to the operating plane of the iron.

24. A hat brim ironing machine comprising a conical ironing roller, a flat faced iron positioned above the ironing roller, means for heating said irons, a lathe spindle whose axis is at all times 55 in uniform angular relation to the operating faces of the irons and adapted to support a hat thereon, means for rotating the lathe, and means for moving the same in an oval path to and from the irons. 60

25. In a hat brim ironing machine, the combination with a pair of irons, of a vertically mounted lathe and hat thereon, means to move the lathe in an oval path, means for rotating the lathe to feed the brim of a hat between the irons, 65 and means adjacent opposite sides of said irons to support and properly guide the brim of the rotating hat between and from the heated irons.

26. In a hat brim ironing machine, combination of a conical shaped rotatable iron and means 70 for heating the same, a flat-faced iron supported to operate in conjunction with the peripheral face of the conical shaped iron, means for heating flat-faced iron, a lathe adapted to support a hat thereon having its brim disposed between the 75

two said irons, means for rotating the lathe, means for moving the rotating lathe and hat to and from the irons at a constantly uniform angle relative to the operating faces of the irons and 5 yielding means for urging said flat-faced iron inwardly against the band line of the hat.

27. In a hat brim ironing machine, the combination with a lathe to support a hat block and hat thereon, of a stationary bearing having a 10 non-rotatable electric heating element mounted thereon, a shaft journaled in said bearing, and a conical iron mounted on said shaft rotatable around and covering said heating element.

28. In a hat brim ironing machine, a lathe 15 adapted to support a hat block and hat thereon,

a pair of irons for ironing the brim of a hat, one of said irons being a conical rotatable iron whose apex meets the axis of the lathe spindle at approximately the base of the hat block to avoid wrinkling of the brim while passing between 5 the irons.

29. In a hat brim ironing machine, a pair of irons for ironing the brim of a hat, a hat block having a central hole therein, an elongated support positioned vertically within said hole, a hat 10 mounted on the block, means for rotating the block and hat, and means for moving the support while in a vertical position toward and from said irons.

PAUL SCHULTZE. 15
